UNITED STATES PATENT OFFICE.

FOREST CHENEY, OF CHICAGO, ILLINOIS, ASSIGNOR TO CHENEY TALKING MACHINE COMPANY, OF CHICAGO, ILLINOIS, A CORPORATION OF ILLINOIS.

SOUND-REPRODUCING MACHINE.

1,407,781.

Specification of Letters Patent. Patented Feb. 28, 1922.

Application filed August 13, 1917. Serial No. 185,853.

To all whom it may concern:

Be it known that I, FOREST CHENEY, a citizen of the United States, and resident of Chicago, in the county of Cook and State 5 of Illinois, have invented certain new and useful Improvements in Sound-Reproducing Machines, of which the following is a specification.

This invention relates to sound reproducing machines and more particularly to speed indicating and control means therefor.

One of the objects of the invention is to improve the control of sound reproducing machines.

15 Another object is to make possible the synchronizing of the various parts of a sound reproducing machine in a simple manner.

Another object is to provide novel control means for machines of the type indicated, 20 adapted to meet the various requirements for successful use.

These and other objects are accomplished by providing in a machine of the class described, the combination of driving means, 25 a speed indicating dial, a pointer movable relative to said dial to indicate speed conditions, and a member for controlling the speed of the driving means, said pointer being movable independently of said member for synchronizing said pointer with said 30 driving means and control member.

The invention is illustrated on the accompanying sheet of drawings in which Figure 1 is a fragmentary sectional view of a sound 35 reproducing machine embodying my invention;

Figure 2 is a fragmentary plan view of my speed indicating and controlling means for such a machine;

40 Figure 3 is a sectional view taken in the plane of line 3—3 of Figure 2;

Figure 4 is a sectional view taken in the plane of line 4—4 of Figure 3, and

45 Figure 5 is a view, parts being in section, taken in the plane of line 5—5 of Figure 3.

The various novel features of my invention will be apparent from the following description and drawings and will be particularly pointed out in the appended claims.

50 Every piece of music which is played or sung has its tempo. The tempo of one piece of music may be entirely different from the tempo of another piece. In order to effectively reproduce a piece of music, for instance, by means of a sound-reproducing ma-

chine, the piece should be reproduced in its proper tempo. It is a common fault that pieces which are reproduced on a talking machine may be played too fast or too slowly. The piece may be marked for a given tempo and the operator of the machine give the speed indicator a corresponding position and still one may be conscious of the fact that the piece is being played too fast or too slowly. In other words, the true tempo of the piece and the speed indication are not in proper accord or in synchronism. Under such conditions it is apparent that a correction of some nature is necessary to rectify the error. For example, the speed 70 indicating pointer may point to the numeral 70 on the speed indicating dial and the motor of the machine be turning the table spindle at the rate of 80 revolutions per unit of time. It is apparent that under these conditions there is a discrepancy of ten revolutions. Heretofore it has been impossible to adjust this discrepancy in any simple manner. However, by means of my invention it is possible to shift the position of the 75 speed indicating pointer with respect to the speed indicating dial, independently of the speed control member for synchronizing the pointer with the driving means and control member.

80 By referring to the accompanying sheet of drawings it will be noted that I have shown a sound reproducing machine 10 having a motor or suitable driving means 11 including a gear 12 mounted upon one end of 85 a spindle 13, to the other end of which is secured a turn-table 14 upon which a record 15 may be mounted for playing. Intermediate the ends of the turn-table spindle 13 is a worm gear 16 in mesh with which is a worm 90 17 mounted upon a suitably supported shaft 18 to which is secured a brake disk 19. Also operatively connected with the shaft 17 is a fly-ball speed governor 20 which is operatively connected to a brake 21, the shoe of 95 which is adapted to frictionally engage the disk 18 for controlling or retarding the speed with which the turn-table 14 is rotated. The brake 21 is pivotally mounted at 22 to a suitable support and is operatively connected 100 with a brake lever 23, the free end of which is bifurcated and embraces the post 24 of speed control and indicating mechanism 25. The free end of the brake lever is also pressed 105 yielding upwardly by a spring 26 against 110

a cam 26 which is fixedly secured to the post 23. From this arrangement it is apparent that if the cam 26 is rotated with respect to the brake lever it will either depress the free end of the brake lever 22 or permit the same to rise under the influence of spring 25 thereby influencing the speed governor 19 and as a result thereof the speed at which the turn-table 14 is driven by the driving mechanism 11.

A stationary speed indicating dial 27 is fixedly secured to a supporting member 28 of the sound reproducing machine, and it will be noted that this speed indicating dial 15 is provided with numbers ranging from 70 to 100. Cooperating with this speed indicating dial and movably mounted thereover is a speed indicating pointer 29 which points to a mark on the dial to indicate the number of 20 revolutions that the turn-table 14 makes in a given unit of time. This pointer 29 has an annular ring 30 which is loosely mounted over an enlarged portion of the post 23 and loosely occupies a corresponding groove 45 25 in the collar portion 32 of a knob 33 mounted over the upper end of the post 23. It will be noted that the pointer 29 also occupies a notch or recess 31 in the collar portion 32. By means of the pointer 29 being received 30 in the notch 31 the pointer is made to travel with respect to the speed indicating dial when the knob 33 is turned. Normally the knob 33 is secured to the post 23 by a set screw 34 which engages a groove 35 in the 35 upper portion of the post 23, and it will be noted that the upper shoulder 36 of the groove 35 is so located relatively to the set screw 34 that unless the set screw 34 is intentionally withdrawn beyond the shoulder 40 36, it is impossible to raise the knob 33 to a point where the pointer 29 is released from the notch or recess 31 in the collar 32 of the knob 33. In other words, it is desirable that the pointer 29 at all times be locked within 45 the notch 31, and the set screw 34 is so positioned with respect to the shoulder 36 to make such conditions possible, and as a matter of fact a spring washer 37 is provided just below the ring portion 30 of the pointer 50 29 to hold the pointer up in the notch 31 and also to hold the pointer out of engagement with the surface of the speed indicating dial 27.

Normally the knob 33 is secured to the post 55 23 by the set screw 34 so that any movement of the knob not only will cause a movement of the pointer 29 to show a change of speed but also will rotate the cam 26 for changing the speed conditions of the driving mechanism 60 through the brake lever 22 and its associated parts. The knob should remain locked to the post 23 so long as the piece of music is being reproduced at the proper tempo with the speed indicating pointer indicating a proper corresponding number of 65

revolutions per unit of time the turn-table is being rotated. However, if there is a discrepancy between the speed indication at the speed dial and the speed with which the turn-table should be rotated for a piece of 70 a given tempo, such discrepancy may be rectified by loosening the set screw 34 sufficiently to permit the knob 33—and thereby the speed indicating pointer 29—to move independently of the cam 26, or in other 75 words, the speed indicating pointer is permitted to move into synchronism with the speed control cam 26 and the motor or driving means 11.

The lower end of the post 23 is provided 80 with a washer 38 to prevent the brake arm from being disconnected from the post 23 at such point. It will be noted, also, that the cam 26 has an effective cam surface extending through substantially 360 degrees, and 85 at the lower end thereof the cam is provided with a stop 39 to prevent the brake lever 22 from snapping upwardly to its extreme high position from its extreme low position. In other words, the cam is permitted 90 to rotate substantially 360 degrees but cannot go beyond that point. The cam must therefore be returned in a counter movement. It might be said that the cam 26 may be reciprocated back and forth through an 95 angle of substantially 360 degrees, making it possible to accurately and delicately adjust the speed at which the turn-table 14 is rotated. A shoulder 40 on the stem 23 and also the upper portion of the cam limit the 100 upward movement of the brake lever 22. It might be stated, also, that the vertical wall 41 of the cam 26 cooperating with brake lever 22 limits the movement of the cam in one direction, while the stop member 39 limits 105 the movement of the cam in an opposite direction.

It is evident that there may be various modifications of the invention herein particularly shown and described, and it is my 110 intention to cover all such modifications which do not involve a departure from the spirit and scope of the invention as set forth in the following claims.

I claim:

1. In a machine of the class described, the combination of a speed indicating dial, a supporting member having a groove therein, a pointer loosely mounted on said supporting member and movable over said speed indicating dial, speed control means mounted on said supporting member, a control knob mounted on said supporting member and having a recess for the reception of said pointer, and means associated with said knob and with the groove in said supporting member to prevent disengagement between the knob and the pointer.

2. In a machine of the class described, the combination of a supporting member, a

- speed controlling cam mounted on said supporting member, and a speed controlling lever operatively connected with said cam member for controlling the speed of the machine, said cam member being movable through substantially 360 degrees, and a stop at the high point of the cam adapted to engage the lever to prevent further rotation of the cam.
- 10 3. A motor regulator comprising a central stem; a cam surrounding said stem; a lever sliding on said stem and operable by said cam; and a governor controlled by said lever, substantially as described.
- 15 4. A motor regulator comprising a central stem; a cam surrounding said stem; a bifurcated lever sliding on said stem and operable by said cam; and a governor controlled by said lever, substantially as described.
- 20 5. A motor regulator comprising a central stem; a sleeve surrounding said stem and having its end formed into a helical cam; a lever sliding on said stem and operable by said stem; and a governor controlled by said lever, substantially as described.
- 25 6. A motor regulator comprising a central stem; a sleeve surrounding said stem and having its end formed into a helical cam; a bifurcated lever sliding on said stem and operable by said cam; and a governor controlled by said lever, substantially as described.
- 30 7. In a regulator for motors, the combination with a post, of a plate through which said post rotatively extends, a pointer on said post and movable therewith relatively to a scale on said plate, a cylindrical sleeve concentrically fixed to said post and having its edge formed into a helical cam, a lever engaging said cam, a spring for yieldingly maintaining said lever against said cam, a governor controlled by said lever, a stem projecting from said post concentrically within said sleeve and slidingly engaged by the end of said lever to guide the same during its movement by said cam and maintain it in radial relation to said sleeve.
- 35 8. In a regulator for motors, the combination with a post, of a plate through which said post rotatively extends, a pointer on said post and movable therewith relatively to a scale on said plate, a cylindrical sleeve concentrically fixed to said post and having its edge formed into a helical cam, a lever engaging said cam, a spring for yieldingly maintaining said lever against said cam, a governor controlled by said lever, and a stop formed on said sleeve at the lower end of
- said cam projecting into the path of said lever.
9. In a regulator for motors, the combination with a post, of a plate through which said post rotatively extends, a pointer on 65 said post and movable therewith relatively to a scale on said plate, a cylindrical sleeve concentrically fixed to said post and having its edge formed into a helical cam, a lever engaging said cam, a spring for yieldingly 70 maintaining said lever against said cam, a governor controlled by said lever, the cam being substantially 360° in extent, the high and low points being joined by a vertical step which serves as a stop to engage the 75 lever to limit rotation of the cam in one direction.
10. In a regulator for motors, the combination with a post, of a plate through which said post rotatively extends, a pointer on 80 said post and movable therewith relatively to a scale on said plate, a cylindrical sleeve concentrically fixed to said post and having its edge formed into a helical cam, a lever engaging said cam, a spring for yieldingly 85 maintaining said lever against said cam, a governor controlled by said lever, the cam being substantially 360° in extent, the high and low points being joined by a vertical step which serves as a stop to engage the 90 lever to limit rotation of the cam in one direction, and a stop upon the high point of the cam to limit rotation of the cam in the opposite direction.
11. In a regulator for motors, the combination with a post, of a plate through which said post rotatively extends, a pointer on 95 said post and movable therewith relatively to a scale on said plate, a cylindrical sleeve concentrically fixed to said post and having 100 its edge formed into a helical cam, a lever engaging said cam, a spring for yieldingly maintaining said lever against said cam, a governor controlled by said lever, a stem projecting from said post concentrically 105 within said sleeve and slidingly engaged by the end of said lever to guide the same during its movement by said cam and maintain it in radial relation to said sleeve, the cam being substantially 360° in extent, the high 110 and low points being joined by a vertical step which serves as a stop to engage the lever to limit rotation of the cam in one direction, and a stop upon the high point of the cam to limit rotation of the cam in the 115 opposite direction.

Signed at Chicago, Illinois this 3rd day of August, 1917.

FOREST CHENEY.
